(57) **CLAIM**

The ornamental design for a stand, as shown and described.

DESCRIPTION

FIG. 1 is an isometric view of a stand showing my new design;

FIG. 2 is another isometric view thereof;

FIG. 3 is another isometric view thereof;

FIG. 4 is another isometric view thereof;

FIG. 5 is a front elevation view thereof;

FIG. 6 is a rear elevation view thereof;

FIG. 7 is a first side elevation view thereof;

FIG. 8 is a second side elevation view thereof;

FIG. 9 is a top plan view thereof; and,

FIG. 10 is a bottom plan view thereof.

The broken lines shown are included for the purpose of illustrating the unclaimed portions of the article and form no part of the claim.

1 Claim, 7 Drawing Sheets(56)
